(74) Attorney, Agent, or Firm — Osha Liang LLP

(57) **CLAIM**

The ornamental design for a speaker for cars, as shown and described.

DESCRIPTION

FIG. 1 is a perspective view of front, bottom and right side of a speaker for cars showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines showing of a speaker for cars are for the purpose of illustrating portions of the speaker for cars and form no part of the claimed design.

1 Claim, 5 Drawing Sheets(56)
